MEANS AND METHOD FOR ORTHOPTIC EXERCISES

Julius F. Neumueller, Quinebaug, Conn., assignor to American Optical Company, Southbridge, Mass., a voluntary association of Massachusetts

Application November 23, 1935, Serial No. 51,245

2 Claims. (Cl. 128—76.5)

This invention relates to improvements in ophthalmic instruments and has particular reference to means and method for training and exercising the eyes and especially the single binocular functions of the two eyes.

One of the principal objects of the invention is to provide improved means and method for exercising the functions of the eyes.

Another object of the invention is to provide a novel and improved device for training the co-ordination of the extrinsic and intrinsic muscles of the eyes for greater efficiency in binocular single vision.

Another object is to provide an improved device for exercising and developing the accommodative functions of the eyes.

Another object is to develop greater reserve of fusional vergence, ductions, etc.

Another object is to provide a novel, simple and improved device for exercising the eyes to bring about increased amplitude of accommodation.

Another object is to provide an improved apparatus and method for bringing about improved coordination between accommodation and convergence for greater efficiency in the performance of the eyes in binocular single vision.

Another object is to train the fusional faculties and stimulate vision in a so-called amblyopic eye, or eye that has lost part of its visual acuity from nonuse.

A further object is to provide an improved apparatus and method of training to break up the habit of suspension of vision in one eye or the other in cases of amblyopia exanopsia, or suspensopsia.

Another object is to provide an improved means and method for exercising the eyes to train them against suspension of vision.

40 A further object is to provide an improved, simple, inexpensive and efficient device capable of use with slight instruction, adapted for exercising the ocular muscles in accordance with the main purpose of my invention.

45 A still further object is to provide a novel apparatus having a plurality of means adapted to be moved before a person's eyes, whereby said means are viewed monocularly while attaining binocular single vision, said means being moved in circular or other paths while being maintained against rotative movement relative to the line of sight of said person's eyes.

Another object is to provide a simple device for exercising the eyes which is readily attachable to commercial instruments having batteries of

interchangeable refractive devices, whereby the latter may be utilized to assist in the exercise.

Another object is to provide an improved eye exercising device in which perception of stereopsis can be increased by causing two fusible objects to be moved in a circular or other path and causing a person to view said fusible objects through prisms which may be varied to vary the exercise of the eyes.

Another object is to provide a device for use with commercial ophthalmic instruments in which the motion of the fixation object can be readily varied at will.

Other objects and advantages of the invention will become apparent from the following description taken in connection with the accompanying drawings, and it will be apparent that many changes may be made in the details of construction, arrangement of parts, steps of the method shown and described without departing from the spirit of the invention as expressed in the accompanying claims. I, therefore, do not wish to be limited to the exact details and steps of the method shown and described, as the preferred forms only have been shown in the way of illustration.

Referring to the drawings:

Fig. I is a perspective view of an assembly showing an embodiment of the invention adapted to be attached to a standard commercial ophthalmic instrument;

Fig. II is a rear elevational view of my invention and shows the various positions the target holder passes through when it is moved to exercise the eyes;

Fig. III is a partial sectional plan view of Fig. II;

Fig. IV is a partial side elevational sectional view along line IV—IV of Fig. III and looking in the direction of the arrows;

Fig. V is a rear elevational view of a modification of the mechanism shown in Figs. II, III and IV for maintaining the target and target holder against rotation relative to the line of sight while the target is moved in circular paths;

Fig. VI is a partial side elevational sectional view taken on line VI—VI of Fig. V;

Fig. VII shows a target adapted to give vergence exercises without guarding against suspensopsia;

Fig. VIII shows a target for giving vergence exercises as well as for training against suspensopsia;

Fig. IX shows a target having similar but disparate parts for stimulating stereopsis;

Fig. X shows a target having non-fusible symbols, such as a red dot and a green dot; and

Fig. XI is a modified form of the target holder for holding a target comprised of separable sections.

The purpose of my invention is to provide a simple and efficient device with the use of which a person's eyes may be readily subjected to the proper exercises to maintain them in condition to perform their proper functions and thus avoid defects in vision due to one or more of the ocular muscles failing to properly or fully coordinate with the other muscles and, also, whereby the ocular muscles may be strengthened and restored to normal conditions and properly perform their functions.

One of the prime causes of ocular discomfort and inefficient vision is the failure of the two eyes to work in unison and produce similar brain stimulations of sight and perception without stress on the muscles of the eyes which control the fusion function. The two eyes may each have normal visual acuity, but if single binocular vision is absent or poor, inefficient vision results and discomfort is experienced.

The single binocular vision function is very closely related to the muscular balance of the eye muscles or innervation balances of the same. It is obvious that if the two eyes have the same visual acuity, efficient and comfortable single binocular vision will depend upon the ability of the person to orient and accommodate both eyes on the same point so that they may receive the same stimulations of sight.

The ability of a person to have and maintain depth perception or stereopsis is very closely related to the ability to fuse together in the brain centers two slightly different images received by each eye. To obtain comfortable and efficient vision an individual must have good stereopsis, good quality and quantity of vergence and absence of suspenopsia. This invention is directed to an improved apparatus and method for exercising the eyes to obtain efficient and comfortable single binocular vision.

Referring to the drawings, in which similar reference characters denote corresponding parts throughout, an embodiment of the invention is shown as an attachment adapted to be used preferably, in conjunction with standard commercial ophthalmic instruments. The attachment cooperates with parts of the commercial instruments to give the desired exercises. Broadly, the essential combination of elements necessary to produce all of the desired results comprises a lens holding frame 11 for holding suitable lenses, a target holder 12 carrying a target 15 and means for moving the target relative to the person in a desired manner while the person is viewing the target through the lenses.

By changing the amplitude of movement of the target relative to the person's eyes, by changing the lenses through which the person views the target and by changing the spacing between the parts of the target viewed monocularly by each eye, very beneficial exercises can be obtained by causing the person to try to follow the movement of the target and maintain single binocular vision or simultaneous binocular vision.

If desired, means may be provided for illuminating the target either intermittently or continuously and the illumination of the parts of the target to be viewed by the individual eyes may be individually varied to provide desired

stimulation for either eye. Such illuminating means are shown in the form of lamps 13 and 14 which may be individually controlled by a control mechanism 16 which controls the current and voltage from any suitable source, not shown.

The lens holding means 11 is of the usual prior art type adapted to be attached to any suitable floor stand by means of the swiveling connector 10.

A sliding frame 17 supports a pair of rods 18 upon which are mounted rotary prism cells 19, and at a distance from these the spherical lens cells 21.

The rotary prism cells 19 each contain a pair of rotary prisms 23 which can be rotated in either direction for different powers by means of knurled handles 24.

Suitably secured to the lens holding means 11 in any convenient manner is a supporting arm 20 26, which carries the target holder 12. The rods 18, carrying the lens cells can be moved with the sliding frame 17 to adjust the lenses to the patient's pupillary distance and an adjustable headrest 27 will assist in maintaining the patient's head in correct position.

The target holder 12 comprises a supporting frame 28, see Figs. I and II, in which is journaled a manually operable mechanism 29 adapted to actuate a target holding frame 31 carrying spring clips or fingers 32 at the outer ends of the latter frame, see Fig. I. The actuating mechanism comprises a hand crank 33, see Fig. III and IV, a stub shaft 30 journaled in an extension 34 of the supporting arm 26, which carries the frame 28, and is connected with an adjustable crank 36 for varying the movement of the frame 31 when the crank 33 is operated. The crank 36 comprises a screw member 37 journaled at each end in a U-shaped member 38 secured to stub shaft 30 and is threadedly engaged by a block 39 pivotally connected to guiding block 41. The frame 31 is carried by the guiding block 41, which is adapted to slide within a slot 42 in a plate 43. The plate 43 has journaled thereon V-grooved rollers 44, see Figs. II, III, and IV, which engage complementary inner surfaces of upright members 46 of the frame 28. The length of stroke of the crank 36 can be varied by operating the knob 35 on the screw 37 to vary the distance of the block 39 from the center of rotation of the crank 36. It will be readily apparent that when the crank is rotated the frame 31 will traverse a circular path while being maintained in a constant angular position by means of the guiding plate 43 and the guiding block 41.

If desired, the arm 26 may be provided with a suitable connection to the lens holding support 11, in order to move the target in any desired path before the eyes. To this end a pivot 60 is provided whereby the target holder 31 may be moved up and down, while the pivot 61 allows movement of the target holder 31 back and forth in the horizontal plane. The pivots 60 and 61 may be selectively held against operation by means of bolt and nut assemblies 62 and 63, respectively, extending through a hole in one member of each respective joint and an arcuate slot in the other and adapted to clamp the respective members of the joints in tight frictional engagement.

It will be readily seen that if the pivot 61 is clamped against operation and the pivot 60 is free to operate the target holder 31 could be moved up and down by means of a suitable knob 75

64. If pivot 60 is locked against operation and the pivot 61 is free to operate, the target holder 31 could be moved from side to side. By allowing both pivots to operate freely, the target holder 5 31 could be moved in any desired path. By simultaneously operating the crank 33 and moving the target holder 31 about the pivots 60 and 61 a great variety of compound motions could be imparted to the target 15.

10 A modification of the target holding mechanism is shown in Figs. V and VI. A hand crank 46 is secured to a stub shaft 47 rotatably mounted in the upper end of the supporting arm 26. A crank arm 48, secured to the shaft 47 carries an 15 idler gear 49, suitably journaled to the arm and adapted to mesh with a gear 51 fixed to the support 26 concentric with the shaft 47 and a gear 52 fixed to a stub shaft 53 journaled in the outer end of the arm 48 and carrying the target holding 20 frame 31. The relative sizes of the pinions or gears 49, 51, and 52 are such that when the arm 48 is rotated the frame 31 will maintain a constant angular relation while describing a circular path. If desired, it will be readily apparent 25 that the construction may be readily varied in order to vary the stroke of the movement of the frame 31.

The target 15 carried on the frame 31 may comprise suitable cards or other indicia having 30 symbols or parts of symbols to be viewed monocularly by each eye to act as binocular fixation means. The various forms which these viewing means may take will be more fully discussed hereafter in connection with the operation of the 35 device. A septum 54 is preferably carried by the lens holding support 11 to prevent either eye from seeing both of the spaced symbols.

In order to illuminate the cards with the lamps 13 and 14, the control mechanism 16, which may 40 be of any usual prior art type, is connected between the lamps and any suitable source of electrical energy. A plug 20 can be attached to any convenient lamp socket and for the purposes of this description should be operated on an alternating current source of suitable voltage. The 45 control mechanism 16 may comprise a suitable transformer for reducing the voltage of the source to the lamps to a convenient and safe potential. A switch 56 may be interposed in the 50 primary of the transformer to shut off the supply to both lamps. A rheostat 57 may be interposed in each of the circuits from the secondary of the transformer to the individual lamps 13 and 14 to vary the brilliancy of each lamp and likewise suitable switches 58 in each circuit may be 55 utilized to shut off completely the illumination of either lamp while the other is illuminated. Although the embodiment of the invention shows the switching means to be hand operated, it is within the scope of the present invention to operate same by automatic means.

In the operation of the device and to carry out the objects of the invention, suitable viewing means such as cards, one end having the letter F and the other the letter L are placed in the target holder under the clips 32. Various cards with different spacings between the letters or separate cards, which may be movable relative to each other to vary the distance therebetween or to vary the prism effect, may be provided. The lamps are preferably provided with suitable shades or reflectors to prevent the light from either lamp from lighting both of the letters or symbols. The variation of illumination for the different parts of the chart or target introduces

difference in visual stimuli in cases of amblyopia.

The patient is seated before the instrument with his head against the headrest 27, and the lateral distance between the lens cells is varied to fit the individual patient by sliding the frame 5 17. Suitable accommodation lenses 21 of powers determined by the amount of accommodation desired during exercising are placed in the cells before the eyes. The cards are held in the card holder at a predetermined distance from the 10 lens cells and then the amount of accommodation can be obtained by using a lens whose focal length, subtracted from dioptic distance between the cards and lenses gives the accommodation desired. For example, the cards are usually 15 placed ten centimeters from the lens cells and if accommodation of plus one diopter is desired, a lens having a focal power of plus nine diopters would be placed in front of the eye. If plus two accommodation is desired, a lens having a focal 20 power of plus 8 would be required, etc. The amount of prism power in front of each eye is then adjusted until the patient is able to maintain single binocular fixation without any stress of the vergence muscles. The chart is then moved 25 in a circular path by operating the crank 33 or 46 thus causing the patient's eyes to rotate around following the fixation objects. This causes very beneficial exercising eye movements by training binocular fixation in any direction 30 and coordination of eye movements. It will be understood that by varying the accommodation in front of the eyes the effective focal plane of the target may be changed while the target is moved to give vergence exercises.

The prisms may be adjusted to give base in, base out or base up or down as desired. It will be apparent that the vergence power of a patient's eyes may be increased by using base in or base out prisms. The control of the vergence 40 exercises can be effected either by means of rotary or loose prisms from one or both eyes or also by mechanical adjustment of the distance between the cards horizontally or vertically.

In cases of persons having an exophoric condition I give prisms base out exercises, thus building up abduction power which acts as a reserve against the exophoria; and conversely for esophoria base in prism exercises are given to build up a reserve of abduction power.

By the use of stereoscopic cards placed in the holder and rotated the stereopsis faculties are exercised and the fusional areas are increased. The amount of prism power can be varied during such exercises to also increase the vergence 55 power by increasing and decreasing the convergence and divergence.

The fixation means used on the target 15 may take a variety of forms in order to obtain the most beneficial results in particular instances. 60 For instance, where it is desired to obtain vergence exercises only without control against suspenopsia, the symbols of the target to be viewed by each eye are identical, for example, ONE on either end of the target, as shown in 65 Fig. VII. The eyes follow the fused symbols and thus when the target is moved and prism power applied the vergence muscles only are exercised.

The targets 15 shown in Figs. VIII and IX are preferably used for obtaining vergence exercises as well as for training against suspension. In Fig. VIII the target comprises a plurality of symbols having identical or similar parts, such as the letters N which fuse together, and other parts such as the letters O and E which are 75

associated with the identical parts to form a completed fixation means when the N's are fused together by the person. Fig. IX shows a target having similar but disparate parts, such as stereoscopic pictures having similar parts of different sizes and/or having different relative positions. The disparity of the retinal images stimulates the stereopsis.

The target 15 shown in Fig. X, having non-fusible symbols, such as a red dot for one eye and a green dot for the other, may be used for eye exercises to train against suspension or amblyopia.

As shown in Fig. XI, symbols of the targets 15 may be movable laterally of each other in order to vary the prism effect produced by the spaced symbols. In such an arrangement the target holder frame 31 may have an upturned outer rim 53a forming a channel at the lower edge of said frame with leaf springs 54a secured to said rim as by welding or soldering at 55 and adapted to press against sections 56 of the target which carry the separate fixation symbols, to hold them against the back of the frame 31. An integral rim 57 turned down from the upper edge of the frame forms a guide channel for the upper edge of the target sections. By moving the sections 56 of the target toward and away from each other, the prism effect may be varied. The outer edge of the lower rim 53 may be provided with a double scale 58 reading from the center toward each end. The scale may be graduated in millimeters and any suitable mark may be placed on the sections 56, or the edges of the sections may 35 serve to indicate the distance between the symbols on the sections 56. If desired, these scales may be calibrated in degrees of prism diopters to indicate the amount of prism effect when the target is at a predetermined distance from the 40 lenses.

It is to be understood the split stereogram type of target may be used for any of the targets particularly adapted for the different exercises above described.

Although an embodiment of the invention is shown in the form of an attachment for a standard commercial ophthalmic instrument, it is to be clearly understood that the invention is not limited thereto and an embodiment may com-

prise a complete and separate instrument in itself embodying the features shown and described.

In the specification and claims the term "lenses" is used in a generic sense to include all kinds of refractive devices, such as prisms, lenses or prisms combined with all forms of lenses.

From the foregoing description it will be apparent that I have provided a novel means and method for exercising eyes to stimulate binocular functions. The apparatus is readily attachable to standard instruments whereby the lenses of such standard instruments may be used.

Having described my invention, I claim: 15

1. An attachment for an ophthalmic instrument, comprising a support adapted to be attached to said instrument, a frame carried by said support having side members, a guide plate mounted on said frame for reciprocatory movement parallel to said side members, a guide block mounted on said plate for movement relative to said plate at right angles to the movement of said plate, target carrying means fixed to said guide block, and means for actuating said block 20 in a circular path lying in the plane of said target carrying means.

2. An attachment for an ophthalmic instrument for use with a person's eyes comprising a support having means for attachment with said instrument, said support constituting in part a frame, a member mounted on said frame for movement in a direction longitudinally thereof, said member having a slideway extending in a direction substantially normal to the first direction of movement, a slide block mounted on said last named slideway, chart carrying means secured to said slide block and means for moving said slide block and chart carrying means in an arcuate path with the said transversely extending slideway and frame maintaining said chart carrying means against rocking movement and from over-turning during the movement thereof so that the horizontal axis of said chart holding means will move into successive positions which are parallel with each other during said arcuate movement. 35

JULIUS F. NEUMUELLER.
